(57) **CLAIM**

I claim the ornamental design for a telescopic lens housing, as shown and described.

DESCRIPTION

FIG. 1 is a perspective view of a telescopic lens housing, showing an embodiment of the new design.

FIG. 2 is a front elevation view of the telescopic lens housing of FIG. 1;

FIG. 3 is a rear elevation view of the telescopic lens housing of FIG. 1;

FIG. 4 is a left side elevation view of the telescopic lens housing of FIG. 1;

FIG. 5 is a right side elevation view of the telescopic lens housing of FIG. 1.

FIG. 6 is a top plan view of the telescopic lens housing of FIG. 1; and,

FIG. 7 is a bottom plan view of the telescopic lens housing of FIG. 1.

The broken line shown in the figures are for environmental purposes only and form no part of the claimed design.
